COMB FOR CARPET SWEEPERS

Berthold Thiele, Milwaukee, Wis., assignor to E. R. Wagner Manufacturing Company, Milwaukee, Wis., a corporation of Wisconsin

Application August 1, 1941, Serial No. 405,002

6 Claims. (Cl. 15—48)

This invention relates to combs for cleaning the rotary brushes for carpet sweepers.

The object of the invention is to provide a comb which may be fabricated as a complete article of manufacture and one possessed of the desired qualities of strength, stiffness, balance, and the like, and yet readily, easily and conveniently assembled with a previously fabricated carpet sweeper case.

In carrying out the present invention the comb is stamped from sheet metal, such as mild steel, which has sufficient resilience to enable the parts to be bent to the final form desired, and bent and rebent as required for assembly and disassembly, and yet is sufficiently stiff, strong, and rigid when the comb is in place and in operation in the sweeper. The comb is made up of an elongated strip-like body portion. At its end the strip-like portion is provided with integral lugs. Pivot studs are staked to these lugs and the lugs also perform the function of stop lugs when the comb is in the sweeper. A row of teeth projects from one longitudinal edge of the strip-like body of the comb. A reinforcing flange is integral with the other longitudinal edge of the strip-like body of the comb and extends substantially at right-angles thereto. At a point intermediate the ends of the flange it has a portion upset or displaced outwardly from the plane of the flange and toward the plane of the strip-like body portion. The displaced portion is preferably curved and serves two functions. It provides a deformable line or zone which has a definite locus on the comb so that the comb may be bent and rebent for purposes of assembly and disassembly without distorting the sections of the reinforcing flange on the opposite sides of the displaced portion and without permanently distorting the body of the comb. The second function of this displaced portion is performed in the assembly wherein it serves as a tie or bridge between the sections of the reinforcing flange on its opposite sides, thereby aiding these reinforcing flanges in stiffening and strengthening the body of the comb.

Other objects and advantages reside in certain novel features of the construction, arrangement, and combination of parts, which will be herein-after more fully described and particularly pointed out in the appended claims, reference being had to the accompanying drawing forming a part of this specification, and in which:

Figure 1 is a view in top plan of the carpet sweeper equipped with combs embodying the present invention, the top or cover of the sweeper

being broken away to show the combs and the manner in which they are combined with the sweeper;

Figure 2 is a fragmentary view in top plan illustrating the manner in which the comb is bent and rebent in order to assemble it with the sweeper, the comb being viewed from above but at an angle and from its flanged side;

Figure 3 is a view similar to Figure 2, but showing the comb completely rebent or straightened and in operative position in the sweeper;

Figure 4 is a fragmentary view in enlarged plan of one end of the comb;

Figure 5 is a view similar to Figure 4 but showing the same portion of the comb in front elevation;

Figure 6 is a sectional view taken on line 6—6 of Figure 5; and

Figure 7 is a sectional view taken on line 7—7 of Figure 6.

Referring to the drawing, the numeral 10 designates a standard or conventional carpet sweeper which has any suitable prefabricated sweeper case 11. The sweeper case 11 has side walls 12 which are formed with transversely aligned bearing sockets 13 adapted to be rotatably interfitted with the pivot studs 14 of combs, designated generally at 15. The combs 15 coact with the rotary brush 16 of the sweeper to clean the same preferably in the manner disclosed in United States Letters Patent 1,898,318, granted February 21, 1933, to E. R. Smith for "Comb attachment for carpet sweepers."

In the manufacture of sweepers, it is usually convenient to assemble the elements of the sweeper with a prefabricated sweeper case, and this is especially true where wooden cases are employed, the parts of which are glued together.

The present invention provides a comb structure which is also completely prefabricated and yet may be readily, easily, and conveniently assembled with a prefabricated sweeper case.

In carrying out these purposes the comb is preferably stamped from sheet metal, such as mild steel, and comprises an elongated strip-like body portion 17. Lugs 18 are integral with the ends of the strip-like body portion and extend at right-angles thereto. Pivot studs 14 are fixedly secured to these lugs 18 and preferably they are staked thereto in the manner illustrated in Figures 6 and 7. A row of comb teeth 19 is integral with and projects from one edge of the strip-like body portion 17 of the comb. A reinforcing flange, designated generally at 20, is in-

tegral with and preferably extends substantially at right-angles to the other longitudinal edge of the strip-like body 17 of the comb. At some point between its ends the flange 20 is punched or upset to provide a combined curved bridge and a deformable zone 21. The metal which constitutes this combined bridge and deformable zone 21 is displaced from the plane of the reinforcing flange toward the plane of the elongated strip-like body 17 of the comb, and it is of curved formation.

As shown in the drawing, it is located mid-way between the ends of the reinforcing flange, and while this is a convenient location, it may be placed at some other point.

When the comb 15 is assembled with and in operation in the sweeper, the element 21 provides a tie or bridge between the sections 20^a and 20^b of the reinforcing flange 20, and aids these reinforcing flange sections in strengthening and stiffening the comb.

During the operations of assembling and disassembling the comb with the sweeper, the element 21 definitely locates a deformable bending line or zone so that, for example, the person assembling the comb with the sweeper may grasp the sections 20^a and 20^b of the reinforcing flange and the adjacent portions of a straight comb and bend the comb to the position shown in dotted lines in Figure 2. This draws or displaces the pivot studs 14 inwardly so that they may be passed between the side walls 11 of the sweeper case until they are brought into registry with the bearing sockets 13 of these side walls, whereupon the comb may be rebent to straighten it out and push the pivot studs 14 into position in their bearing sockets 13. During this operation any distortion of the sections 20^a and 20^b of the reinforcing flange 20 is prevented since the bending zone is definitely located in the element 21 and substantially along the center line thereof. The alined portion of the strip-like body 17 of the comb is bent, of course, but straightens out on rebending, and its structure and its capacity for its intended purposes remain unimpaired. The final position of the straightened comb, in the assembly, is illustrated in Figures 1 and 3.

With such a construction, the comb may be completely prefabricated with its body portion, teeth, reinforcing flange, mounting and stop lugs and pivot studs all in final form and assembly and yet may be very readily and easily assembled with a prefabricated sweeper case.

While I have shown and described one construction in which the invention may be advantageously embodied, it is to be understood that the construction shown has been selected merely for the purpose of illustration or example, and that various changes in the size, shape, and arrangement of the parts may be made without departing from the spirit of the invention or the scope of the subjoined claims.

I claim:

1. As an article of manufacture, a comb for use with carpet sweepers provided with a reinforcing flange having a portion intermediate its ends displaced from the plane of the flange to define a deformable zone of definite locus and also a bridge between the sections of the flange on the opposite sides of said displaced portion.

2. As an article of manufacture, a comb for use with carpet sweepers comprising an elongated strip-like body, a row of teeth integral

with and projecting from one longitudinal edge of the strip-like body, and a reinforcing flange integral with the other longitudinal edge of the body and having a portion intermediate its ends displaced from the plane of the flange and toward the plane of the body and of curved formation to define a deformable or bending zone of definite locus and also a bridge or tie between the sections of the flange on the opposite sides of said displaced portion.

3. As an article of manufacture, a comb for use with carpet sweepers comprising an elongated strip-like body, lugs integral with the ends of the body, pivot studs permanently secured to the lugs and projecting laterally therefrom, a row of teeth integral with and projecting from one longitudinal edge of the strip-like body, and a reinforcing flange integral with the other longitudinal edge of the body and having a portion intermediate its ends displaced from the plane of the flange and toward the plane of the body and of curved formation to define a deformable or binding zone of definite locus and also a bridge or tie between the sections of the flange on the opposite sides of said displaced portion.

4. In combination with a carpet sweeper having a casing including end walls provided with transversely alined bearing sockets, a comb constituted of sheet metal and comprising an elongated strip-like body, lugs integral with the ends of the body, pivot studs permanently secured to the lugs, projecting outwardly therefrom and adapted to be rotatably interfitted with the bearing sockets, a row of teeth integral with and projecting from one edge of the strip-like body, a reinforcing flange integral with the other longitudinal edge of the body, a portion of the reinforcing flange intermediate its ends being upset to divide the reinforcing flange into two sections and to provide a curved and deformable bridge between said sections, said bridge being deformable to provide for assembly and disassembly of the pivot studs of the comb with the bearing sockets and bridging the sections of the reinforcing flange in the assembly to aid the reinforcing flange in strengthening and stiffening the comb.

5. In combination with a carpet sweeper having a casing including end walls provided with transversely alined bearing sockets, a comb constituted of sheet metal and comprising an elongated strip-like body, lugs integral with the ends of the body, pivot studs permanently secured to the lugs, projecting outwardly therefrom and adapted to be rotatably interfitted with the bearing sockets, a row of teeth integral with and projecting from one edge of the strip-like body, a reinforcing flange integral with the other longitudinal edge of the body, a portion of the reinforcing flange intermediate its ends being upset from the plane of the flange and toward the plane of the body to define a bending zone of definite locus, and a bridge between the sections of the flange on the opposite sides of said upset portion.

6. As an article of manufacture, a comb for use with carpet sweepers constituted of resilient metal and provided with a reinforcing flange having a curved formation intermediate its ends affording a bending zone of definite locus and also a bridge or tie between the sections of the flange on the opposite sides of said formation.

BERTHOLD THIELE.
